UNITED STATES PATENT OFFICE.

MORRIS SILVERMAN, OF CHICAGO, ILLINOIS, ASSIGNOR TO LYNN A. WILLIAMS, OF CHICAGO, ILLINOIS.

SKYLIGHT CONSTRUCTION.

1,219,177.

Specification of Letters Patent. Patented Mar. 13, 1917.

Application filed May 8, 1916. Serial No. 96,038.

To all whom it may concern:

Be it known that I, MORRIS SILVERMAN, a citizen of the United States, residing at Chicago, in the county of Cook and State of Illinois, have invented a certain new and useful Improvement in Skylight Construction, of which the following is a full, clear, concise, and exact description, reference being had to the accompanying drawings, forming a part of this specification.

My invention relates to means for flexibly supporting the glass panes in a skylight structure to permit of relative movement between the panes and the supporting members when expansion and contraction of the parts occur.

One of the objects of the invention is to provide means whereby the flexible mountings, or more specifically the springs, may be located on the inner side of the glass panes, thus protecting the mountings from corrosion, etc.

A further object of the invention is the provision of a flexible mounting which permits the glass panes to have movement in either direction at right angles thereto, or in other words, to have movement either inwardly or outwardly relative to their supporting means.

These and other features of my invention will be clearly set forth in the following description in which reference is made to the accompanying drawing, wherein—

Figure 1 is a perspective view of the device of my invention, some of the parts being broken away to more clearly illustrate the construction thereof, and

Fig. 2 is a vertical cross sectional view of the device taken longitudinally through the parts illustrated in Fig. 1.

Similar characters of reference refer to similar parts throughout both views.

In Fig. 1, 3 illustrates a support of wood, concrete or metal, to which is secured an angle iron 4. Fixed to the angle iron 4 by means of the clips 5 and 6 is a channel bar 7, which lies at right angles to the supporting member 3. The screws 8 and 9 which connect the clips 5 and 6 respectively with the channel 7 extend through the channel and into an inverted U member 10, as illustrated in Fig. 1. This inverted U member is provided at 11 with a central aperture through which extends a bolt or rod 12 ter-

minating at its lower end in a flange or enlarged head 13.

The upper end of the rod 12 is provided with the shoulder 13' from which extends a threaded shank 14 arranged to cooperate with the nut 15. A compression spring 16 is disposed around the lower end of the rod 12 and arranged to act between the inverted U member 10 and the flange 13 of the rod 12, so that there is a tendency, due to the tension of the spring 16, to force the rod or bolt 12 downwardly. As most clearly illustrated in Fig. 1, the rod 12 extends between the edges of the glass panes 17 and 18 and through apertures contained in the felt strips 19 and 20. Extending over the top of the strip 19 is a corrugated metal strip 21 running, as do the felt strips 19 and 20, along the entire edges of the glass panes 17 and 18. A similar corrugated metal strip is provided at 22 on the underside of the felt strip 20. These corrugated strips 21 and 22 contain apertures registering with the apertures provided in the felt strips 19 and 20, so that the rods 12 have free play through the packing means. Resting against the underside of the corrugated strip 22 is an inverted cup 23 provided with a central aperture 24, through which the bolt or rod 12 extends. Acting between the channel bar 7 and the underside of the cup 23 is a helical compression spring 25, which, as illustrated in Fig. 1, extends around the upturned portion of the inverted U member 10. This spring 25 is capable of withstanding approximately 240 pounds per square foot without deflection, so that the weight of a man placed upon the corrugated strip 21 will not cause downward movement of the glass panes at the point at which the weight is applied. The spring 25 is made somewhat stronger than the spring 16, so that the rod 12, when the parts are assembled as shown in Fig. 1, will be lifted above the base channel bar 7 against the tension of the spring 16. The nut 15 which screws upon the shank 14 serves to engage the upper face of the strip 21 and thus prevents downward movement of the rod 12 independently of the packing means and thus of the glass plates.

The channel bar 7 which extends under and parallel with the adjacent edges of the glass panes 17 and 18 serves the purpose of catching the moisture of condensation or

any moisture which may succeed in passing the packing strips 19 and 20. It will be observed from the description thus far given that all the springs are positioned on the inside of the glass panes, so that they are entirely protected from the weather. On account of the double spring mounting the panes are permitted to move in both directions, either upwardly or downwardly 10 against the tensions of the springs 16 and 25 respectively. Due to the inverted cup 23, the pressure of the spring 25 is concentrated at only a small area of the under corrugated strip 22, so that the panes are permitted to 15 rock easily upon their support when expansion or contraction of the parts occurs.

Due to the large tension of the spring 25 I have found it advisable in assembling the parts to provide a bolt or rod 12 which can 20 be enlarged longitudinally. With this end in view I construct the rod 12 of two parts, a lower part 26 and an upper part 27. The lower portion 26 is provided with an upwardly extending threaded shank 28 arranged to thread into the upper portion 27, which is bored and threaded at 29 to receive 25 the shank. In assembling the device the channel bar 7 is first fixed to the supporting members 3 as stated, and the inverted U 30 member together with the lower portion 26 of the rod 12 and spring 16 placed in position. The top portion 27 of the rod 12 is then screwed onto the shank 28 to the position illustrated in Fig. 2, whereupon the spring 35 25 and the inverted cup 23 are placed around the rod 12. The packing means and the glass plates are then put in place over the upper end of the rod 12 and the nut 15 screwed onto the shank 14.

40 After the underside of the nut 15 engages the shoulder 13' of the rod 12 further rotation of the nut causes the upper portion 27 of the rod 12 to thread downwardly onto the shank 28, rotation of the lower portion 45 26 of the rod 12 being prevented due to the enlarged lower end or flange 13 which, upon rotation of the portion 26, strikes against the inverted U member 10. As the upper portion 27 is thus lowered into position the 50 nut 15 engages the upper face of the corrugated strip 21 and forces the glass plates downwardly. At the same time, however, the lower end 26 of the rod is forced upwardly against the tension of the spring 16, 55 so that when the parts are assembled the flange 13 extends a certain distance above the base of the channel bar 7 to permit downward movement of the glass panes against the tension of the spring 25 when this becomes necessary.

So far as I am aware, no means has been employed in the past for flexibly supporting the glass panes from the underside, so as to permit inward movement of the panes relative to their supporting members. The

devices employed have used stationary or non-flexible means against which the underside of the strip 22 or the packing means rests. I wish it to be understood, however, that the arrangement of the spring 16 and its coöperating parts can be used without the employment of the spring 25, the lower face of the strip 22 resting, in such a construction, against a stationary support such as has been employed in the past.

Having thus described my invention, what I claim as new and desire to secure by United States Letters Patent is:

1. A skylight structure comprising a glass pane, a helical compression spring forming 80 a support therefor on the inner side thereof and a second helical compression spring disposed on the inner side of the pane and concentric with the first mentioned spring for pressing the pane against the support. 85

2. In a skylight construction the provision of means for flexibly supporting the adjacent edges of the glass panes comprising, a channel bar lying parallel with and under the adjacent edges of the glass panes, an inverted U member carried by the bar and provided with a central aperture, a rod extending between the glass panes and through the aperture in the U member, a flange on the inner end of the rod, a helical compression spring interposed between the flange and the U member tending to move the rod inwardly, an enlarged head at the outer end of the rod and a helical compression spring disposed around the U member 95 and rod between the underside of the glass panes and the channel bar.

3. In a skylight construction the provision of means for flexibly supporting the adjacent edges of glass panes, comprising, 105 a channel bar lying parallel with and under the adjacent edges of the glass panes, an inverted U member carried by the bar and provided with a central aperture, a rod extending between the glass panes and through the aperture in the U member, a flange carried at the inner end of the rod, a helical compression spring disposed around the rod 110 between the flange and the U member tending to move the rod inwardly, an enlarged head at the outer end of the rod, an inverted tapering cup resting against the underside 115 of the glass panes and having a central aperture through which the rod extends, and a helical compression spring disposed 120 around the U member and rod and between the inverted cup and the channel bar.

4. In a skylight construction the combination of glass panes, a support on the inner side thereof, a longitudinally contractible rod extending between the edges of the panes, a flange provided on the inner end of the rod, a spring abutment carried by the support and positioned intermediate the flange and the glass panes, a compression 125 130

- spring interposed between the flange and the abutment tending to move the said rod inwardly, and means carried at the outer end of the rod for engaging the outer sides of the glass panes.
5. In a skylight construction the combination of glass panes, a support on the inner side thereof, a longitudinally contractible bolt extending between the edges of the panes, a flange provided on the inner end of the bolt, a spring abutment carried by the support and positioned intermediate the flange and the glass panes, a compression spring interposed between the flange and the abutment tending to move the bolt inwardly, and a nut provided on the outer end of the rod.
6. In a skylight construction the provision of means for flexibly supporting the adjacent edges of glass panes comprising a channel bar lying parallel with and under the adjacent edges of the glass panes, an inverted U member carried by the bar and provided with a central aperture, a longitudinally enlargable rod extending between the glass panes and through the aperture in the U member, a flange provided on the inner end of the rod, a compression spring interposed between the flange and the U member tending to move the rod inwardly, an enlarged head at the outer end of the rod and a compression spring disposed around the U member and rod and between the underside of the glass panes and the channel bar.
7. In a skylight the combination of glass panes, a support therefor on the inner side thereof, a helical compression spring between the underside of the panes and the support, and a longitudinally enlargable rod extending between the panes of glass and secured to the support, said rod being provided at its outer end with an enlarged portion arranged to engage the outer faces of the glass panes.
8. In a skylight construction the provision of means for supporting the adjacent edges of glass panes comprising packing means covering the edges of the panes on the outer and inner sides thereof, a channel bar on the inner side of the glass, a rod extending between the panes through the packing and provided with an enlarged outer end bearing against the outer packing, a flange carried by the inner end of the rod, a spring abutment carried by the channel bar and disposed intermediate the flange and the said inner packing, a compression spring interposed between the flange and the abutment, and a helical compression spring carried by the channel bar for supporting the underside of the inner packing.
9. In a skylight the provision of means for supporting the adjacent edges of glass panes comprising, packing means covering the edges of the panes on the outer and inner sides thereof, a channel bar on the inner side of the glass, a rod extending between the panes through the packing and provided with an enlarged outer end bearing against the outer packing, a flange carried by the inner end of the rod, a spring abutment carried by the channel bar and disposed intermediate the flange and the said inner packing, a compression spring interposed between the flange and the abutment, and a second compression spring interposed between the channel bar and the underside of the inner packing.
10. In a skylight construction the provision of means for supporting the adjacent edges of glass panes comprising, packing means covering the edges of the panes on the outer and inner sides thereof, a channel bar on the inner side of the glass, a rod extending between the panes through the packing and provided with an enlarged outer end bearing against the outer packing, a flange carried by the inner end of the rod, a spring abutment carried by the channel bar and disposed intermediate the flange and the said inner packing, a compression spring interposed between the flange and the abutment, and a second compression spring interposed between the channel bar and the underside of the inner packing.
11. In a skylight construction the combination of a support, glass panes, a compression spring acting between the insides of the panes and the support and a second compression spring acting between the support and the outside of the panes, both springs being concentrically disposed on the inner side of the glass panes.
- In witness whereof, I hereunto subscribe my name this 6th day of May, A. D. 1916.
